GARMENT PRESSING MACHINE

Clarence M. Clarke, Syracuse, N. Y., assignor to
 United States Hoffman Machinery Corporation,
 New York, N. Y., a corporation of Delaware

Application November 29, 1949, Serial No. 130,030

7 Claims. (Cl. 38—41)

1

This invention relates to pressing machines, particularly fluid operated garment and laundry pressing machines in which a head pressing element is movable toward a garment supporting buck, and has for one of its objects the provision of a simple, dependable and safe actuating mechanism including a fluid motor, as a cylinder and a piston movable in the cylinder in two distinct stages at different degrees of fluid pressure to effect successively the closing of the press and then the application of heavy pressure between the head and buck. It is further an object of the invention to transmit power from the motor to the press head in two mechanical stages, respectively in action simultaneously with the said two stages of operation of the motor. A further object is to provide a press of the nature described effectively safeguarded against the possibility of the operator getting his hands between the pressing elements while heavy pressure is being applied.

A further object is to provide reliable pressure regulating means for the actuating fluid to the motor, thus to insure initially an adjustable minimum fluid pressure for motor operation and thereafter, at will, a further supply of pressure fluid at a selected higher pressure.

A still further object is to provide a regulating mechanism of the character described comprising simple and reliable means for automatically locking the regulating means in either its condition of initial or later selected adjustment, dependent upon the progressive manipulation and operation of the press.

Another object is the provision of a novel and simple control system, partly manual and partly automatic, for the attainment of the practical and safe operation of a press of the nature described.

Other objects will be in part obvious and in part pointed out hereinafter.

The invention accordingly comprises the construction and arrangement of parts hereinafter described and claimed.

In the drawings, which represent one suitable embodiment of the invention,

Fig. 1 is a front elevation of the press in the closed position of the head in relation to buck;

Fig. 2 is a right side elevation thereof, partly broken away more clearly to show the head operating mechanism when in closed and locked position and after the application of heavy pressure;

Fig. 3 is a diagrammatic view of the operating mechanism including the fluid pressure con-

trolling valves and fluid pressure adjusting devices in operative relation to certain press head operating and operated parts, the press being in the position obtaining at the end of the first stage of motor operation.

Referring to the drawings it will be seen that the present garment press comprises a press head 11, adapted to swing downwardly into pressing relation with a fixed press element or buck 12. The head 11 is fixed to a yoke or head lever 13, fulcrumed between its ends, as at 14, upon a press frame 15. A link 16 pivotally connected at its upper end, as at 17, to the yoke 13 transmits motion to close the press. The press when closed to predetermined proximity with the buck is automatically locked in position, as will appear, and when released from its closed position will open under the reactive force of an opening spring 18. In closing the press "zero" pressure is employed, i. e. the press head is initially closed under power sufficient only to overcome the tension of a head counterbalancing spring 19.

The lower end of link 16 pivotally supports a cam roller 20 movable, during the closing of the press, through two stages of a scroll cam 21, mounted on the frame 15, which cam guides the movements of the lower end of the link. The cam roller 20 is carried by a cross head 22 of a single-acting reciprocating pneumatic or other fluid motor 23, comprising a cylinder 24 and a piston 25, the piston rod 26 of which is secured to cross-head 22.

It is to be noted that the first or upright longer portion of the cam 21 is inclined to the horizontal about 75° and the second or shorter upper portion, at an angle of about 5°. Travel of the cam follower up the steep incline of the cam from position #1 to position #2 (Fig. 3) causes a rapid closing of the press with a minimum of pressure; while the slower movement of the roller over the upper wedge-like portion from position #2 to position #3 (Fig. 2) slowly transmits the final movement of the piston rod to the head 11 and develops heavy pressure between head and buck, not only because of the advantage of the cam but also because this portion of the movement can only take place after the pressure of the air supply to the motor has been increased.

In order to protect the operator from injury, as when laying a garment between the pressure elements as they are brought together, power presses of the type described are usually provided with so-called "two-hand" control requiring the manipulation of a pair of complementary motor

valves simultaneously in order to apply the final pressure of the motor to the press head.

It is natural and well known that the majority of press operators prefer to use one hand only to close the press, so that the operator may make his last minute adjustment in laying the garment with his other hand, but this is often dangerous as the operator's hand may be caught under the press head and be severely injured.

In the present press "two-hand" control of the kind just described is avoided and equal or superior protection is had by the employment of the novel press operating control devices now to be described.

Referring again to the drawings, and particularly to Fig. 3 thereof, it is to be noted that air from a suitable pressure supply (of approximately 60# p. s. i.) is brought to the press by a main supply line 30 directly to an adjustable pressure regulating valve 31. From valve 31 air under initial adjusted pressure flows via branched conduits 33 and 33' to a manually controlled motor inlet valve 32 and to a special locking valve 34. Press regulating valve 31 may be actuated by hand operated lever or handle 35 directly or in a preferred manner by means of a hand lever 36 having a ball handle 37 which is positioned to the right at the front of the press. Lever 36 is fulcrumed at 38 on a bracket 39 supported by the frame 15 and is connected by link 40 at 41 in lever 36 and to lever 35 at 42.

Pressure regulating valve outlet lines 33 and 33' are always supplied with a certain minimum adjusted pressure from line 30 (for example, 15 to 20# p. s. i.) by manually setting an adjustment screw 43 in the same manner as in standard pressure regulating valves. Lever 35 is normally biased toward closed position of valve 31 and towards screw 43 by means of a spring 44.

This minimum is the desired pressure at which fluid is supplied to the motor 23 during the first part of its stroke to close the press without substantial pressure between the press elements. Valve lever 35 is normally locked in an inoperative position by means of an arcuate rack 45 carrying teeth 46 on its outer edge and a downwardly and inwardly sloping notch 47 on its inner peripheral edge. The notch 47 is adapted to engage a pin 48 projecting from the side of lever 35. Rack 45 is normally held against pin 48 by a return spring 49 for plunger 50 movable in an adjustment lock cylinder 51. Enough clearance is allowed between the shoulder of notch 47 and pin 48 to permit slight pressure adjustment by adjustment screw 43.

In operation, the adjusted low pressure air (15-20#) from line 33 is supplied to the motor via admission valve 32 by downward pressure upon a hand lever 52. This valve 32 is a diaphragm locked intake-exhaust valve of well known construction having its intake port normally closed and its exhaust port normally open, which valve is provided with a diaphragm chamber 28 which when supplied with fluid pressure maintains the admission valve in open position, as will appear. When the adjusted minimum pressure in line 33 is passed to the motor by depressing lever 52 and opening valve 32, pressure fluid flows to the motor cylinder by way of pipe 54. This pipe leads to the inlet port 24 of the cylinder 23 and via the by-pass valve 55 to the end of a cushioning cylinder 56 formed in the cylinder head 57, and containing a plunger 58 as indicated in the drawings.

Low pressure in line 54 to the motor causes

movement of piston 25 to effect closing of the press. The press is also locked under this pressure should the press elements come into close enough proximity to one another (about $\frac{1}{8}$ of an inch). Should the operator release valve control lever 52 before the locking point is reached the intake port of valve 32 will close and the exhaust will open, the air being then released from the power cylinder. Under these conditions the press head will return to its open position under spring action.

After the press has been partially closed under light pressure and roller 20 has climbed to the top of the closing section of the cam (position #2) and the press heads have been brought together to the predetermined degree of proximity, the arrival of the press head at this point will effect opening of the locking valve 34 through the upward movement of a rod 59 pivotally connected at its upper end by adjustable means 60 to the yoke 13, as shown, and pivotally connected at its lower end at 61 to operating lever 62 of locking valve 34. The locking valve is thus opened, permitting passage of pressure fluid via conduit 33' through the valve to pipe line 63 leading to a cross-fitting 64. Between cross 64 and valve 34 is inserted a needle valve or other restricted orifice fitting 65. Valve 34 is similar in construction to valve 32, omitting the diaphragm chamber 28 of the latter.

When valve 34 is opened, as above described, a restricted flow of fluid from line 33' through needle valve 65 to the cross 64 occurs, whence the flow is branched by way of pipes 66, 67 and 68. The compressed air from line 66 will flow to the diaphragm chamber 28 of motor admission valve 32 to lock the valve in its open motor-operative position and thus permit the operator to release the hand lever 52, which will then remain in its depressed position. The compressed air through line 68 will flow to lock cylinder 51, associated with regulating valve 31, causing the rack teeth 46 to engage and be held in any adjusted position by a spring pressed pawl 69 mounted on pressure regulating valve lever 35 to hold that lever against return from any adjusted pressure control position to which it may have been moved.

Normally, the regulating valve will be depressed by manual operation of lever 35 to provide the desired degree of heavy pressure, less than line supply pressure, to the power cylinder 23 as soon as the operator has completed his lay of a garment. This heavy fluid pressure causes the power motor to finish its stroke and the cam roller 20 to move to a final position, as #3. It should be understood then that the locking valve 34 is moved to open position to lock the admission valve 32 whenever the press heads have closed to a predetermined nearness, whether the regulating valve 31 has been adjusted to heavy pressure or not.

Whenever air from valve 34 enters cylinder 51 it will cause piston 50 to swing rack 45 to the left, bringing the rack teeth 46 into contact with pawl 69 and releasing the pin 48 from the slot 47 to permit downward movement of lever 35 to effect any desired degree of opening of valve 31.

The operator may now depress the lever 36 to cause the desired higher pressure to be delivered to the head and buck elements of the press because high pressure air will flow through line 33 to the locked in open position valve 32, then through the latter to the power cylinder 23 causing the roller to move along the upper

portion of cam 21, thus applying heavy pressure. When pressure regulating valve lever 35 is released from manual pressure it will remain in its depressed position because pawl 69 is engaged with rack 45. The press will now remain closed under regulated high pressure as long as desired. However, lever 35 may be moved down at any time while in locked position, to attain more pressure.

Pipe line 67 leads to a normally closed exhaust valve 70 operated by a hand lever 71. The compressed air from line 63 passes through branch line 67 to exhaust valve 70 but without effect unless valve 70 be opened by depression of lever 71 by the operator. Then the air will be exhausted from the diaphragm chamber 28 to cause closing of intake port of valve 32 and opening the exhaust port thereof. This action permits escape of air from cylinder 23, thus permitting the press to open. At the same time, the air from locking cylinder 51 will be released, return spring 49 will withdraw rack 45 from engagement with pawl 69, pressure regulating valve 34 will return to normal position and pin 48 will relock in its inoperative or initial position.

The needle valve or restricted orifice in 63 is required because the capacity of release exhaust valve 70 must be greater than the supply of compressed air from line 63, thus permitting air from cylinder 51 and diaphragm chamber 28 of valve 32 to escape, regardless of the air pressure existing for the moment in line 63.

It will be understood, of course, that valve 34 remains open as long as the press is locked in closed position.

From the foregoing it will be seen that the present invention is well adapted to attain the aims and objects hereinbefore set forth and has many advantages arising from the particular manner of effecting the closing of the press by both fluid pressure and cam action, and by the controlled operation of the fluid motor and the cam roller under either light or heavy fluid pressure to attain alternatively either "zero" or any desired heavy pressure between the pressing elements of the press.

Although the invention has been described with considerable particularity in the foregoing specification and by reference to the accompanying drawings, it must be understood that the invention is not limited to these specific details, but cover modifications coming within the scope of the appended claims and their equivalents.

I claim:

1. In a garment press having cooperative pressing elements comprising a garment supporting buck and a relatively movable head carried by a yoke pivotally mounted with respect to said buck, in combination, a single cylinder fluid actuated motor having a reciprocating piston, motion transmitting mechanism comprising a cam follower and a link cooperatively connected with said piston and yoke to effect the closing of said elements, said piston being movable in two distinct stages under different degrees of fluid pressure, first to close said elements to a predetermined nearness and then to complete the movement thereof to apply heavy pressure to a treated garment, a normally closed and manually operable intake valve for said motor adapted to be locked by fluid pressure in open condition, a source of compressed air or other pressure fluid, pressure control mechanism including a regulating valve normally conditioned

to supply fluid from said source to said intake valve at a predetermined reduced pressure to close the press to said predetermined point, a normally closed locking valve connected to transmit fluid between said source and said intake valve and operably associated with said regulating valve and said intake valve and means operatively associated with said motion transmitting mechanism and operable in response to said near approach of said elements to effect operation of said locking valve to cause the intake valve to lock in open position, normally inoperable manual adjusting means for said pressure control valve and means rendering said adjusting means operable after the operation of said locking means to supply fluid at a selected higher pressure to said intake valve and motor, whereby the final closing of the press is accomplished under heavy pressure.

2. In a garment press having cooperative pressing elements comprising a garment supporting buck and a relatively movable head, in combination, a fluid motor for actuating said head, a pressure regulating mechanism including pneumatic locking means, an intake valve for supplying pressure fluid from said pressure regulating mechanism to said fluid motor and having a locking chamber, a press actuated valve connected to be operated in response to movement of said movable head, a supply conduit between said regulating valve and said press actuated valve, a discharge conduit for said press operated valve including pressure reducing means having a restricted passage therethrough, piping leading separately from said pressure reducing means to said pneumatic locking means of said regulating mechanism and to said locking chamber of said intake valve and also to a manually operated exhaust valve for releasing the operating fluid from the fluid motor, said exhaust valve having a discharge opening substantially larger in area than the restricted passage through said pressure reducing means.

3. A garment or laundry press comprising a frame, a presser arm pivoted intermediate its ends on said frame, a stationary pressing element mounted on said frame, a movable pressing element mounted on said presser arm for cooperative engagement with said stationary pressing element, a toggle member comprising an inextensible link and a longitudinally extensible fluid motor pivotally connected respectively to said presser arm and said frame at their remote ends and pivotally joined together at their adjacent ends by means including a cam follower, a two-step cam associated with said frame and said follower adapted to guide said follower to close said press elements into "zero" pressure engagement during an initial operation of said motor and subsequently to close said press elements into heavy pressing engagement during a final operation of said motor, means for manually admitting fluid to said motor at an adjusted pressure sufficient to perform the said initial operation of said motor and other means for manually admitting fluid to said motor at a substantially higher adjusted pressure to perform the said final operation of said motor.

4. In a garment press as in claim 1, in which cooperative means is provided, operable after the operation of said locking valve, to release said normally inoperable manual adjusting means and permit manual operation of said regulating valve.

5. In a garment press as in claim 1, in which

said pressure control mechanism comprises an operating lever, detent means normally holding said lever at a minimum pressure adjustment of said regulating valve, fluid pressure operated means operably associated with said locking valve to act, after the operation of said valve, to release said lever from said detent means, thereby to permit manual adjustment of said lever to increase fluid pressure to said intake valve, and other detent means rendered operative upon the release of said lever to hold said lever and valve in the said position of increased pressure adjustment.

6. In a garment press as in claim 5, in which said pressure control lever releasing means comprises a fluid pressure actuated plunger, means cooperative with said plunger and said pressure control lever to lock said lever in an adjusted reduced pressure position or in an adjusted higher pressure position, means normally biasing said mechanism to the first of said positions and conduit means connecting said plunger with said locking valve whereby upon operation of said locking valve to lock said intake valve, pressure fluid is made available to actuate said plunger.

7. In a garment press in combination, cooperative pressing elements one of which is relatively movable with respect to the other to press garments laid therebetween, a power actuator comprising a single fluid cylinder and piston therefor, a scroll cam having two cam follower guiding sections angularly displaced with respect

to one another, a cam follower operably associated with said piston and said cam to transmit the power from the motor to one of said press elements to close the press rapidly during the traverse of the follower through the first said guiding section of the cam, a supply of pressure fluid, pressure reducing means normally adjusted to supply fluid from said source at a predetermined reduced pressure to said motor cylinder to effect movement of the cam follower through the said first section of the cam and manually operated means for supplying to the cylinder pressure fluid from said source at a higher adjusted pressure than said predetermined reduced pressure to effect movement of the cam follower through the said second section of the cam thereby to apply heavy pressure between the pressure elements, as a result both of the increased application of force during the traverse by the cam follower of said second cam portion and by the increased adjusted pressure supplied to said cylinder.
